US0D1007342S

(12) **United States Design Patent** (10) Patent No.: **US D1,007,342 S**
(45) Date of Patent: ** Dec. 12, 2023

(54) **REMOTE CONTROLLER FOR AIR CONDITIONER**

(71) Applicant: **FUJITSU GENERAL LIMITED**, Kawasaki (JP)

(72) Inventor: **Shingo Iwasa**, Kawasaki (JP)

(73) Assignee: **FUJITSU GENERAL LIMITED**, Kawasaki (JP)

(**) Term: **15 Years**

(21) Appl. No.: **29/795,804**

(22) Filed: **Jun. 21, 2021**

(30) **Foreign Application Priority Data**

Dec. 21, 2020 (JP) ..... 2020027583 D
May 31, 2021 (JP) ..... 2021011627 D

(57) **CLAIM**

The ornamental design for a remote controller for air conditioner, as shown and described.

DESCRIPTION

FIG. 1 is a perspective view of a remote controller for air conditioner showing my new design;

FIG. 2 is a front view thereof;

FIG. 3 is a rear view thereof;

FIG. 4 is a right side view thereof; a left side view being a mirror image;

FIG. 5 is a top view thereof; and,

FIG. 6 is a bottom view thereof.

The broken lines in the drawings illustrate portions of the remote controller for air conditioner which form no part of the claimed design.

1 Claim, 5 Drawing Sheets
